(57) **CLAIM**

The ornamental design for a food storage container, as shown and described.

DESCRIPTION

FIG. 1 is a perspective view of a food storage container showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the food storage container where the food storage container is in a configuration of use; and,

FIG. 10 is an exploded perspective view of the food storage container.

The dash-dash broken lines in the drawings depict portions of the food storage container that form no part of the claimed

(Continued)

design. The broken lines in the FIG. 10 depict environment of the food storage container that form no part of the claimed design.

1 Claim, 10 Drawing Sheets
